COMMERCIAL BUILDING

Henry Dreyfuss, South Pasadena, Calif., and Julian G. Everett, Dobbs Ferry, N.Y., assignors to Cities Service Research and Development Company, New York, N.Y., a corporation of New Jersey

Filed Aug. 11, 1959, Ser. No. 57,138

Term of patent 14 years

(Cl. D13—1)

FIGURE 1 is a front perspective view of a commercial building showing our new design; and

FIGURE 2 is a rear elevational view thereof.

FIGURE 3 is an enlarged fragmentary perspective view of the top portion of the building shown in FIGURE 1.

The dominant features of our design reside in the portions shown in full lines.

The side of the building not shown in FIGURES 1 or 2 is substantially the same as the side which is shown.

We claim:

The ornamental design for a commercial building, substantially as shown and described.
